UNITED STATES PATENT OFFICE

2,530,687

PACKER HEAD CONCRETE PIPE MACHINE

William Bryan Dixon, Houston, Tex.

Application July 29, 1946, Serial No. 686,901

1 Claim. (Cl. 25—36)

1

This invention relates to a packer head concrete pipe machine.

One object of the invention is to provide a concrete pipe making machine of the packer head type that will form a section of pipe out of semi-dry mixed concrete quickly and easily with a minimum of loss in malformed pipe.

Another object of the invention is to provide a concrete pipe machine of the character described having a novel turntable mounted in a novel manner on one leg of the framework, greatly facilitating the handling of jackets in which the pipe is formed.

Another object of the invention is to provide a machine of the character described having a novel means for controlling the longitudinal movement of the packer screw.

Another object of the invention is to provide a machine of the character described having an automatic means for disengaging the bell former upon completion of the formation of a length of pipe, permitting the operator to move the turntable supporting the jackets moving the formed pipe out of the machine and the empty jacket into position with a minimum of effort.

Another object of the invention is to provide a machine of the character described having a material hopper of novel construction and that may be readily locked to the jacket in which the pipe is formed during the pipe making operation and may be quickly and easily released after the section of pipe has been formed.

The above and other objects will be apparent from the following description and illustrated in the accompanying drawings, wherein:

Figure 1 is a front elevational view of the pipe making machine.

Figure 2 is a side view of the material hopper and controls therefor taken on the line 2—2 of Figure 1.

Figure 3 is a side elevational view, partly in section.

Figure 4 is a top plan view of the turntable taken on the line 4—4 of Figure 3, and

Figure 5 is a bottom cross sectional view of the bell former taken on the line 5—5 of Figure 3.

Referring now more particularly to the drawings, the numerals 1, 2 designate the front legs of the framework constructed preferably of channel iron. The rear legs, 3, are preferably constructed of angle iron and are tapered inwardly at a point approximately midway of the length thereof and have the motor platform legs 4 bolted or riveted thereto. A suitable brace 5, formed of steel, connects the motor platform 6 and the front and rear legs.

2

A packer shaft, or screw 7, is mounted between the front legs and has the upper portion thereof threaded, preferably with acme threads, and a keyway 8 is formed longitudinally in the packer shaft 7 the full length of the threaded portion. A suitable motor 9 is mounted on the motor platform 6 and is adapted to impart rotation to the pulley 10 through the pulley 11. The pulley 10 is mounted on the shaft 12 which is in turn mounted on suitable bearings as 13, on the motor platform. A clutch 14 releasably connects the pulley 10 with the shaft 15 mounted in the bearings 16. On the opposing end of the shaft 15 is a suitable bevel gear 17 in mesh with and adapted to rotate the bevel gear 18. The gear 18 is connected to the packer shaft 7 by a suitable key (not shown) which rides in the keyway 8 of the packer shaft 7, permitting the shaft 7 to pass freely longitudinally through the gear 18. A clutch control rod 19 is fulcrumed at 20 and has the control handle 21 convenient to the hand of the operator. A pair of internally threaded split nuts 22, 22 are mounted on the framework immediately beneath the motor platform and embrace the packer shaft 7. A pair of adjustable arms 23, 23 are pivotally mounted at one end to each of said split nuts and at the other end to control bars 24, 24. The extension bars 25, 25 are fulcrumed at one end to suitable platforms 26, 26 in the legs 1, 2 and at the other end to the control bars 24, 24. A cross bar 27 connects the lower ends of said control bars 24, 24 and a lever 28 mounted on said cross bar 27 permits the split nuts to be opened and closed. The adjustable arms 23, 23 may be so adjusted that when the split nuts are moved to closed position around the packer shaft, the connecting point of the adjustable arms 23, extension bars 25 and control levers 24 will move below level, locking the split nuts 22, 22 in position around the packer shaft.

A counterbalance 29 is connected to a swivel 30 which is mounted on the upper end of the packer shaft 7.

A trowel 31 is fixedly mounted on the lower end of the shaft 7, and a piston 32 is mounted on the shaft 7 approximately midway of the ends thereof. A cross bar 33 between the front legs 1, 2, supports a stop 34 against which the piston 32 abuts, limiting the downward movement of the shaft 7.

A material tray 35' is mounted within the framework formed by the legs and tapers slightly downwardly from the rear legs to the front legs and is open between the front legs to permit the material to be moved out of the tray. A material

hopper 35 is mounted on the cross bar 36 by means of the connecting bars 37, 38. Controlling levers 39, 40 are fulcrumed to the cross bar 36 by means of the link 38'. A counterbalance 41 is also connected to the cross bar 36. A stop 42 is mounted on the leg 2 to limit the movement of the control 39 when the material hopper is lowered. The movement of the control 39 past center against the stop 42 will lock the material hopper in position. The movement of the control lever 39 raises or lowers the hopper 35. A depending lip 43 extends downwardly from the hopper 35 and is shaped to fit snugly over the top of a jacket.

The base of the legs of the machine are set preferably in concrete. A turntable 44 is rotatably mounted on one leg, 1, of the machine, adjacent the base thereof, and has a pair of jacket receiving plates 45, 45 mounted on the turntable. Upstanding arms 46, 46 permit the turntable to be rotated by the operator. Upstanding lugs 47, 47 in the plates 45, 45 receive notches (not shown) in the jackets 48, 48. Ports 49, 49 in the plates 45, 45 permit a bell former 50 to pass up through the plates to form the bell of the pipe section in the jacket. The turntable has each end thereof notched as at 51, 51 and a spring latch 52 of any suitable construction, is mounted on the opposing leg 2 of the framework to yieldably lock the turntable in operating position.

The legs of the machine are mounted in concrete and beneath the machine a well is provided as 53, a portion of the machine extending beneath the surface of the floor 54 of the building or shop in which the machine is located, and the turntable is located a few inches above the floor surface as shown in Figures 1 and 3 of the drawings.

A bell former 50 is mounted on the shaft 55 which extends beneath the surface 54 and an axial alignment with the packer shaft 7. A bevel gear 56, keyed on said shaft by means of the key 57 mounted in the keyway 58 has a suitable bushing as 84, formed of brass or similar material which may be employed to prevent wear of the gear. A tail pipe 59 is anchored to the bottom of the well and receives the end of the shaft 55. A zerk fitting 60 for introducing grease or lubricant into the tail pipe may be provided. A shaft 61, mounted on suitable bearings as 62, 62 has the bevel gear 63 on one end thereof in mesh with the gear 56. A pulley 64 mounted on the opposing end of said shaft is rotated by the motor 65 which is mounted on the cross plate 66 fixedly secured to the legs 4, 1. A pulley 67 is in rotating connection with the pulley 68 mounted on and adapted to rotate the shaft 69. The shaft 69 is mounted on the legs 4, 1 by means of suitable bearings 70, 70 and a pulley 71 is mounted adjacent one end of said shaft. A belt 72 connects said pulley 71 with the pulley 64. A clutch 73, controlled by the clutch bar 74 and clutch lever 75, moves the shaft 69 into and out of rotation with the said pulley 67.

A yoke 74 is pivotally mounted on the shaft 55 beneath the bell former. A connecting arm 75', fulcrumed adjacent said yoke, extends therefrom to the rear of the well 53. A counterbalance 83 is mounted on and adjacent to the far side of the connecting arm 75'. A connecting arm 76 extends upwardly and is releasably connected with a lever 77 which is fulcrumed to a cross bar on the leg 4. The free end of the lever 77 is pivotally connected to the arm 78 which is connected to the cross arm 79. A yoke

80 mounted on the cross arm 79, embraces the packer shaft 7 and is adjustably mounted at one end on the extension 81.

A door 85 is provided in the material hopper with suitable locking means 86, for cleaning the hopper tray.

In making concrete pipe, the semidry material is deposited on the material tray 35. The jackets 48, 48 are mounted on the turntable 44 and one of the jackets moved into position in axial alignment with the packer shaft. The hopper 35 is lowered onto the jacket and locked in position thereon, the lip 43 fitting snugly over the top of the jacket. The lever 28 is moved to open the split nuts 22, 22 and the packer shaft will drop into lowered position, the counterbalance 29 providing sufficient counter-balance to provide a smooth and gentle lowering of the packer shaft. The lower end of the packer shaft on which the trowel 31 is mounted enters the jacket 48 on the turntable, and the lower end of the trowel, commonly referred to as the core, enters the top of the bell former. As the packer shaft is lowered, the piston 32 disengages the yoke 82 and the counterbalance 83 will lower the arm 75' raising the bell former up through the turntable and into operating position within the jacket. When the piston 32 reaches the stop 34 the further downward movement of the shaft 7 will be blocked. The operator draws some of the material from the hopper into the jacket and moves the clutch levers 21 and 75 into operating position. The trowel 31 will distribute the material around the jacket wall and the bell former will pack the material in the lower end of the jacket forming the bell of the section of pipe. The bell former need operate only a few seconds and the operator disengages the clutch 73 which stops the bell former. The operator then moves the split nuts 22, 22 into closed position by means of the lever 28, causing the packer shaft to move upwardly through the split nuts 22, 22 while turning the trowel 31 as it moves the trowel upwardly, thus distributing the concrete evenly around the walls of the jacket and the core of the trowel packing same tightly therein, forming the pipe. As the packer screw reaches the extent of its upward movement, the piston 32 will abut against the yoke 80 and move the bell former 50 downwardly out of engagement with the jacket 48. As the trowel comes up through the material hopper, the operator disengages the clutch 14, and manually moves the hopper 35 upwardly through the lever 39, and turns the turntable a half revolution, moving the filled jacket out of position and the empty jacket into position beneath the packer shaft. A cart 82 may be employed to move the full jacket out of the way and an empty jacket in its place on the turntable, while the operator is forming another section of pipe. When the empty jacket is in position, the split nuts are again opened and the packer shaft lowered into position and the process repeated.

The embodiments of the invention herein shown and described are to be regarded as illustrative only, and it is to be understood that the invention is susceptible to variation, modification and change within the scope of the appended claim.

What I claim is:

In a concrete pipe making machine, an upstanding framework, a rotatable shaft mounted longitudinally therein, the upper portion of said shaft being threaded, an abutment on said shaft adjacent the lower termination of said threads,

releasable means engaging said threads to elevate said shaft, counterweights thereon to assist in said elevation, a motor in geared connection with said shaft, bell packing means for forming a bell on the lower end of said pipe, independent driving means for rotating said bell packer, a fulcrumed lever mounted on said framework and having a yoke adjacent one end thereof embracing and adapted to be contacted by the abutment on said shaft when said shaft is elevated to a point adjacent its extreme upward position, a train of lever connections secured to the other end of said fulcrumed lever in connection with the bell packer and adapted to move the bell packer out of engagement with the pipe to be formed upon extreme upward movement of the shaft and to move said bell packer into engagement with the pipe to be formed upon downward movement of the said shaft.
